UNITED STATES PATENT OFFICE.

JOHN TEMPLE, WILLIAM M. MILLS, AND ATLAS L. STOUT, OF MIDDLE-TOWN, OHIO.

IMPROVEMENT IN WATER-WHEELS.

Specification forming part of Letters Patent No. 37,833, dated March 3, 1833.

To all whom it may concern:

Be it known that we, JOHN TEMPLE, WILLIAM M. MILLS, and ATLAS L. STOUT, of Middletown, in the county of Butler and State of Ohio, have invented a new and useful Improvement in Water-Wheels; and we do hereby declare the following to be a full and exact description of the same, reference being had to the accompanying drawings and the letters of reference thereon.

Figure I represents a horizontal plan view of the wheel in section. Fig. II is a vertical section of the same with our improvement.

Our invention relates to certain improvements in that description of water-wheels known as the "central-discharge horizontally-submerged wheel"; and the invention consists in the peculiar construction and formation of the flanges which constitute the top and bottom portions of the wheel; also, in the combination of these flanges with the cyma-reversa scroll-buckets, whereby greater advantages are obtained by the use of any given force or head of water, while at the same time the construction is such as to be made or cast of metal with greater facility and at less expense, as herein more fully described.

In the drawings, A indicates the top flange or top part of the wheel. B refers to the lower flange or portion of the wheel, and C indicates the buckets. O is the opening through which the water is discharged at the center of the wheel.

The two rims or flanges A B are inclined downward toward the center of the wheel at an angle of about thirty-three degrees. The lower or bottom flange forms at the base of the buckets an inclined plane from the periphery of the wheel to the annular discharge-space within, and the top flange or rim has the same general inclination, as before stated, but is of a curved form, its inner surface being concave, as may be seen in the drawings at Fig. 2.

Although a good result may be secured by giving to the internal face of the upper flange a circular or cup-formed depression, we have found in practice that this surface of the flange, to operate to the best advantage, should be curved on its internal surface or face from the periphery of the wheel to the annular discharge-opening, so that a vertical line drawn from a point at the center of the

upper flange equidistant from the adjacent buckets, and from the outer and inner edges of the said upper rim or flange to a corresponding point on the lower rim or flange, will be of greater length than vertical lines drawn from the outer or inner edges of these flanges; in other words, the distance between the two rims or flanges is greater at the center, owing to the curved form of the upper flange, than the distance at their edges.

The important objects attained in this improvement, which have proved highly successful in use, are the combination of such elements in the construction of water-wheels as will secure not only all the force of the direct action of the water upon the face of the scroll-buckets, but, in addition to this percussive action, in a great measure, convert the reaction or "backlash" to aid in propelling the wheel by giving a downward direction to the water in its reaction, and thus augment the force exerted by the hydrostatic pressure and gravity upon the inclined face of the bottom flange or rim of the wheel.

By the above-described formation and construction we combine the advantages in a submerged horizontal water-wheel of the direct action and backlash, together with the hydrostatic pressure or gravity of a column of water, to propel the wheel in its forward revolutions. This improved wheel is intended to be used with the improved sluice invented and patented by John Temple, February 8, 1859, said patent being numbered 22,901.

It will be readily understood that this water-wheel, as seen in the drawings, is composed of the two annular inclined rim or flanges, having the configuration, respectively, as above described, and between said flanges or rims is interposed a series of cyma-reversa or scroll-buckets with corresponding ingress and egress passages.

In the operation of the wheel the water is admitted to the buckets through the adjustable gates and sluices, (described in the patent of John Temple, above referred to,) and acts directly upon the faces of the scroll-buckets by its full percussive force, is then deflected downward by means of the curved or concave face of the top flange or rim, thus adding to and augmenting the force of gravity exerted by the body of the water passing down the

inclined plane of the lower or bottom flange, which also impels the wheel in its forward revolutions.

One of the practical advantages of the depression or curved form of the upper flange, besides that of deflecting the current of water toward the inclined plane of the bottom flange, is its tendency to retain a moving column of water, which shall act by hydrostatic pressure upon the inclined bottom flange, which is an inclined plane, declining not only from the periphery of the wheel toward its center, but also inclining tangentially from the ingress to the egress or discharge-opening, the former being in advance of the latter as respects the direction of the movement of the wheel. By this means, also, we secure a continuously wedging and gravitating action of the water from the time it has expended its percussive force upon the scroll-buckets until it reaches the finally-impinging point where it is freely discharged.

Having fully described our invention, what we claim as our improvement in submerged horizontally-revolving water-wheels is—

1. The combination of the curved or concave top flange or rim, A, with the inclined straight flange or rim B, constructed and operating in the manner and for the purposes substantially as described.

2. The combination of the flanges or rims A, B, constructed, as set forth, with the cyma-reversa or scroll-buckets C, in the manner and substantially as specified.

In testimony whereof we have hereunto subscribed our names this 18th day of October, A. D. 1862.

JOHN TEMPLE.
WM. M. MILLS.
